UNITED STATES PATENT OFFICE.

JUSTUS F. NE PAGE, OF SEATTLE, WASHINGTON.

DESIGN FOR A STREET-LIGHTING POST.

Application filed December 23, 1925. Serial No. 15,834. Term of patent 8½ years.

To all whom it may concern:

Be it known that I, JUSTUS F. NE PAGE, a citizen of the United States, and a resident of Seattle, in the county of King and the State of Washington, have invented a new, original, and ornamental Design for Street-Lighting Posts, of which the following is a specification, reference being had to the accompanying drawings, forming a part thereof.

Fig. 1 is a side elevation of a lighting post showing my new design.

Fig. 2 is a transverse section of the same.

I claim:

The ornamental design for a street lighting post, as shown.

JUSTUS F. NE PAGE.
